COMBINED MICROFILM READER STAND AND REEL STORAGE CONSOLE

Norman B. Bodinger, Denver, Colo., assignor to Information Handling Services, Inc., Englewood, Colo., a corporation of Colorado

Filed Aug. 31, 1967, Ser. No. 8,444

Term of patent 14 years

U.S. Cl. D33—19
Int. Cl. D6—01

FIG. 2.

FIG. 1.

FIG. 3.

FIG. 4.

FIG. 5.

FIGURE 1 is a front elevation of a combined microfilm reader stand and reel storage console showing my new design;

FIGURE 2 is a top plan view thereof;

FIGURE 3 is a rear elevation thereof;

FIGURE 4 is a right side elevation; and

FIGURE 5 is a left side elevation.

I claim:

The ornamental design for a combined microfilm reader stand and reel storage console, as shown.
